Primary Examiner — Janice Hallmark(74) *Attorney, Agent, or Firm* — McGarry Bair PC**CLAIM**

The ornamental design for a ceiling fan blade, as shown and described.

DESCRIPTION

FIG. 1 is a top perspective view of a ceiling fan blade, showing my new design;

FIG. 2 is a bottom perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

The broken lines in the drawings depict environmental subject matter only and form no part of the claimed design.

1 Claim, 4 Drawing Sheets(56)
